Gregory Costa, Jr., Metuchen, Bernard S. Bresky, Fanwood, and Martin Schnur, West Orange, N.J., assignors to Costa Ice Cream Company, Woodbridge, N.J., a corporation of New Jersey

Filed Apr. 11, 1967, Ser. No. 6,641

Term of patent 14 years

(Cl. D58—12)

FIG. 1 is an elevational view of a hexagonal shaped food carton showing two adjacent sides of our new design;

FIG. 2 is an elevational view thereof showing another side and portions of the sides shown in FIG. 1; and

FIG. 3 is an end elevational view thereof.

The dotted line right-hand border portion in FIG. 1 represents a repeat pattern of the border portion shown on the left-hand side of said figure. The upper and lower dotted line portions shown in FIG. 2 represent the same ornamentation shown in the upper and lower portions of FIG. 1, respectively. The dotted line portions of FIG. 3 represent the same ornamentation, on a reduced scale, as that shown in FIG. 1. The other end portion of the carton has the same ornamentation as that shown in FIG. 3.

We claim:

The ornamental design for a hexagonal shaped food carton, as shown and described.
